UNITED STATES PATENT OFFICE.

PAUL A. HABERL, OF DENVER, COLORADO.

DESIGN FOR A SOUVENIR-SPOON.

SPECIFICATION forming part of Design No. 36,249, dated March 24, 1903.

Application filed January 21, 1903. Serial No. 140,035. Term of patent 7 years.

To all whom it may concern:

Be it known that I, PAUL A. HABERL, a citizen of the United States of America, residing at the city of Denver, Arapahoe county, and State of Colorado, have invented and produced a new, original, and ornamental Design for a Souvenir-Spoon; and I do declare the following to be a full, clear, and exact description of the invention, such as will enable others skilled in the art to which it appertains to make and use the same, reference being had to the accompanying drawing, which forms a part of this specification.

This invention relates to a design for a souvenir-spoon.

The drawing is a front plan view of a spoon, showing my new design.

As shown in the drawing, the leading or material feature of my design consists of the following representations: At the top of the spoon the representation of a female figure holding a spear, mountains appearing at the right, water at the left, a ship in the distance, and a small bear in the foreground, the whole being surrounded by a scroll, a large bear

immediately below the above representation. Below the bear is a gold-washing scene in which two men are shown, one of them operating a machine; an orange-branch about midway of the spoon-handle; a large tree below the orange-branch. All of the above representations are surrounded and separated by ornamental scrollwork, which gives the edges of the handle a curved ornamental contour; two flower-stems, with blossoms, between the tree and the spoon-bowl; the Cliff House and seal-rocks on the bowl of the spoon, and a steamer on the water in the distance.

Having thus described my invention, what I claim, and desire to secure by Letters Patent, is—

The ornamental design for a souvenir-spoon as herein shown and described.

In testimony whereof I affix my signature in presence of two witnesses.

PAUL A. HABERL.
